CLAIM

The ornamental design for a battery module assembly for household hybrid photovoltaic and storage converter as shown and described.

DESCRIPTION

FIG. 1 is a front, right, top perspective view of a battery module assembly for household hybrid photovoltaic and storage converter according to the present application, showing our new design;

FIG. 2 is a rear, left, top perspective view thereof;

FIG. 3 is a front view thereof;

FIG. 4 is a rear view thereof;

FIG. 5 is a left side view thereof;

FIG. 6 is a right side view thereof;

FIG. 7 is an enlarged top view thereof;

FIG. 8 is an enlarged bottom view thereof;

FIG. 9 is an enlarged partial view of the area identified as 9 in FIG. 1;

FIG. 10 is an enlarged partial view of the area identified as 10 in FIG. 2; and,

FIG. 11 is an enlarged partial view of the area identified as 11 in FIG. 2.

The broken lines in the drawings depict portions of the battery module assembly that form no part of the claimed design.

Additional broken lines in FIGS. 1 and 2 are to demarcate areas shown enlarged in FIGS. 9 to 11 and are not part of the claimed design.
